[57] **ABSTRACT**

A fingertip and fingerpad toughening and callusing device is described. The device is a substantially cylindrical element which can be readily positioned in the palm of the hand. Either a portion or all of the surface of the cylindrical element comprises segmented ridges which are pressed and/or rolled upon the fingertip and fingerpad thereby producing a toughening and callusing effect. The device is particularly useful for musicians that play string instruments such as the guitar, mandolin, bass, cello and the like.

FIG. 1

FIG. 2

SECTION A-A

FIG. 3

FINGERTIP AND FINGERPAD TOUGHENING AND CALLUSING DEVICE

BACKGROUND OF THE INVENTION

This invention relates to a fingertip and fingerpad toughening and callusing device. In one aspect, this invention relates to a fingertip and fingeredpad toughening device which can be employed by instrumentalists of string instruments. Another aspect of this invention relates to a device for the toughening and callusing of the fingertips and fingerpads of instrumentalists of metal string instruments.

It is well known that instrumentalists of string instruments can develop fingertip and fingerpad soreness as a result of pressing upon or strumming the strings of the instrument. The fingertip soreness is particularly noticeable in the left hand and hence limits the players ability to produce clear tones and chords. The soreness produced by pressing or pulling off the strings with the left hand and/or picking and strumming with the right hand can become extremely painful and hence with respect to the novice such soreness can be greatly discouraging.

The soreness due to pressing, rubbing, pushing and picking the metal strings of instruments such as the guitar, mandolin and the like is particularly painful and hence often prevents the novice from continuing with the study of the musical instrument.

There are many ways of toughening and callusing the skin. For example, toughening lotions, liquids, salves and the like are known. Athletes such as sprinters and basketball players, for example, can use liquids which are painted on the soles of the feet in order to produce calluses. These toughener and callus producing devices can cause a decrease in the sensitivity of the fingers and hence may not be suitable for instrumentalists of string instruments since sensitivity in the fingers can be important in tone production and control.

Thus, there is a need for improved methods of quickly toughening and callusing the fingertips and fingerpads (both terms hereinafter being referred to as fingertips) since many of the known means have several disadvantages for string instrumentalists.

SUMMARY OF THE INVENTION

In accordance with this invention a device is provided for callusing and toughening the fingertips without adversely affecting their sensitivity. The device comprises an element which can readily be positioned in the palm of the hand. Either a portion or all of the surface of said element comprises sequented ridges, which ridges upon being pressed, rolled or rubbed on the fingertips effects toughening and callusing of said fingertips.

It is therefore an object of this invention to provide a fingertip callusing and toughening device.

It is another object of this invention to provide a device for toughening and callusing the fingertips of string instrument instrumentalists without adversely affecting the sensitivity of said fingertips.

It is still another object of this invention to provide a fingertip toughening and callusing device for instrumentalists of stringed instruments which comprises metal strings.

It is yet another object of this invention to provide a device for toughening and callusing the fingertips of guitarists.

DESCRIPTION OF THE PREFERRED EMBODIMENTS

The above and other objects are accomplished with a device which comprises an element having on a portion of its surface or periphery a plurality of segmented ridges (teeth) which can be rolled, pressed or rubbed upon the fingertips in order to effect toughening and callusing of the fingertips without causing soreness of the fingertips.

In the accompanying drawings the preferred embodiments of the invention are illustrated.

FIG. 1 is a plan view of a preferred embodiment.

FIG. 2 is a view of section A—A of FIG. 1.

FIG. 3 is a detailed view of the teeth or segmented ridge section which covers a portion or all of the surface or periphery.

Referring more in detail to the accompanying drawings, FIG. 1 illustrates a portion of the periphery 1 of a cylindrical element. The Figure illustrates a series of immediately adjacent longitudinal grooves 2 said grooves running from one end of the element to the other end of the element, and a plurality of immediately adjacent grooves 3 transverse to said longitudinal grooves thereby forming a series of teeth or segmented ridges 4 the segmented ridges in each successive row being substantially collinear with respect to each other.

FIG. 2 is a cross section through a transverse groove taken from A—A of FIG. 1. In accordance with one preferred embodiment the longitudinal grooves 2 appear on a portion of the periphery of the cylindrical element. In accordance with another preferred embodiment FIG. 2 illustrates that the callusing and toughening device is hollow 5 thereby promoting lightness. The portion of the periphery not crossed with longitudinal grooves can either be smooth 6 or the transverse grooves can be continuous.

FIG. 3 is a detailed view of the teeth or segmented ridges 4 formed by cutting the surface of the device with the longitudinal grooves 2 and the transverse grooves 3. In accordance with a preferred embodiment of the invention, and as illustrated in FIG. 3, the segmented ridges or teeth are in the shape of triangular prisms.

The device when rubbed, but preferably rolled or pressed into the fingertips will over a short period produce a toughening and callusing effect. The effect will enhance and facilitate chord construction and tone production, and will substantially decrease finger soreness. Such advantages are especially desirous for the beginning musician.

In accordance with a preferred embodiment of the invention, the device, when in use will advantageously simulate feelingwise the strings of a stringed instrument, and especially guitar strings. The effect, if all four fingers are pressed upon the device, will advantageously simulate feelingwise the fingering of a guitar chord or the chord for other stringed musical instruments. In order to obtain these unexpected advantages the longitudinal grooves should be substantially parallel. In order to obtain the callusing and toughening effect the grooves need not be parallel however the desirable feeling of pressing upon strings will be diminished.

The parallel grooves normally extend from one end of the element to the other end of the element and the plurality of said grooves, for comfort reasons generally cover about half the periphery of the element, thereby

avoiding toughening and callusing of the palm. The transverse grooves can either completely encircle the element or cover only that portion necessary to form the segmented ridges. The complete encirclement by the transverse grooves would facilitate rolling the element against the fingertips.

In accordance with the preferred embodiment as described in FIGS. 1 to 3, the element is preferably hollow in order to promote lightness and ease of carrying on one's person while the device is not in actual use. As a result of the ease of carrying the element, the instrumentalist can readily improve the conditions of his fingertips at any time the left hand is not in use, for example, while riding in a car, watching television, taking a walk and the like.

For reasons of comfort it is preferable that the device be substantially cylindrical. The cylindrical shape facilitates rolling between the thumb and remaining fingers or between the palm of the hand and the fingers, and eliminates uncomfortable corners. The element or body, however can have many variations, for example, the body can be ellipsoidal, cubical, polyhedral, and the like.

The element or body can be made from a variety of materials, for example, wood; metal such as stainless steel, aluminum, brass, copper etc.; polymeric materials such as high density polyethylene, polypropylene, polyesters, polyurethanes, polycarbonates, etc. and the like.

The element can be prepared by any means well known in the art of shaping materials, the element can be molded or forged. The grooves can be formed during the molding or forging operations or thereafter. The transverse grooves can be formed by threading and thereafter the element is grooved longitudinally thereby forming teeth or segmented ridges.

The finished element can be pressed or rolled into the fingertips for any length of time. Preferably, the element should be pressed into the fingertips from about 10 to 50 seconds and repeated as often as possible in order to produce sufficient callusing and toughness, without any undue oreness and any detrimental loss in

fingertip sensitivity with respect to the fingering of the strings.

The dimensions of the element can vary greatly. Typically, the element will be cylindrical and be from about 1 cm to about 6 cm in diameter and from about 5 cm to about 11 cm long. The longitudinal grooves can be from $\frac{1}{2}$ mm to about 2 mm in width and the length of each ridge or tooth can be from about 1 mm to about 3 mm.

10 The invention has been described in detail with particular reference to certain preferred embodiments thereof, but it will be understood that variations and modifications can be effected within the spirit and scope of the invention.

15 I Claim:

1. A device for callusing and toughening the fingertips comprising an element suitable for positioning in the palm of the hand having on a portion of its periphery a plurality of immediately adjacent longitudinal parallel grooves and a plurality of immediately adjacent grooves transverse to said longitudinal grooves thereby forming a series of segmented ridges which can be pressed against the fingertips.

2. The device of claim 1 wherein said element is cylindrical.

3. The device of claim 2 wherein said plurality of longitudinal grooves extend from one end of the cylinder to the other end of the cylinder and said grooves extend over about one half the periphery of the cylinder.

4. The device of claim 3, said device being a polymeric material.

5. The device of claim 1 wherein said segmented ridges have the shape of triangular prisms.

6. The device of claim 5 wherein said longitudinal grooves are from about $\frac{1}{2}$ mm to 2 mm in width and the length of each triangular prismatically shaped segmented ridge is from about 1 mm to about 3 mm.

7. The device of claim 1 wherein said cylindrical element is about 5 cm to about 11 cm long and from about 1 cm to about 6 cm in diameter.

UNITED STATES PATENT OFFICE
CERTIFICATE OF CORRECTION

Patent No. 3,756,223

Dated September 4, 1973

Inventor(s) FRANK J. CARBONE

It is certified that error appears in the above-identified patent
and that said Letters Patent are hereby corrected as shown below:

Col. 1, line 51, "sequented" should read --segmented--;
line 59, "adversey" should read --adversely--.

Col. 2, line 31, "cylindrial" should read --cylindrical--.

Col. 3, line 41, "toughess" should read --toughness--;
line 42, "orenness" should read --sorenness--.

Signed and sealed this 4th day of June 1974.
